ROTARY CRUDE OIL BURNER

Lewis Motley, Staines, England

Application April 4, 1935, Serial No. 14,723
In Great Britain April 6, 1934

3 Claims. (Cl. 158—77)

This invention relates to rotary crude oil burners and has for its object to provide a burner of increased efficiency, and of the kind having a rotary conical atomizer.

5 The burner is of the type having an oil tube extending axially through the apparatus in which the supply of air to the atomized oil leaving the cone is delivered over the end of the conical nozzle by a fan, and according to the present invention such air supply after being drawn in through the central portion of the back of the fan casing passes through the fan casing, there being provided at the opposite or front side of the fan casing stationary curved blades arranged 10 to direct the air inwards and towards the nozzle and then outwards over the end of the atomizing cone in the reverse direction of rotation to it to atomize the oil film leaving the conical nozzle.

The invention is illustrated by the accompanying drawing in which Figure 1 is a partly sectional general view of the device, Figure 2 a view of the fixed air blades and Figure 3 an end view of a cap fitting on the end of the central oil tube. In this drawing *a* is the central hollow feed shaft or tube which rotates with the rotary element of the fan *b*. The oil tube *a* at its end remote from the fan *b* rotates over a fixed oil supplying tube *c*. The oil supplying pipe *c* is fixed in outlet member *p* of a pump *p* and 20 extends along the bore of the rotary oil tube *a* the part within the tube being provided with a screw thread or spiral groove *a* of square section on the outer surface of which the oil tube *a* rotates. The pitch and direction of the spiral 25 groove are arranged to return oil tending to escape along the fixed tube *c*, to the rotary tube *a*.

The other end of the oil feed shaft *a* is fixed in the rear end of a conical atomizer *d* by a cap nut *d* which screws on the end of the tube *a* 40 and engages the inner end of the conical atomizer *d* and so holds it on the tube *a*.

The cap nut *d* is provided with oppositely disposed holes *d* *d* drilled in the cap nut *d* other than radially and arranged to deliver oil 45 on the inner surface of the conical atomizer *d*, when fed therethrough by the oil pump *p*.

The hollow oil feed shaft *a* has preferably a taper bore the larger end being in the conical atomizer.

50 The oil feed holes *d* *d* rotate with the fan and operate as a centrifugal thrower tending to create a partial vacuum in the shaft *a* and thereby preventing oil working back past the stationary feeder *c* at its inlet end, and so on for 55 instance to the gear box of the oil pump.

In the present invention, instead of bringing the air axially to the free end of the conical atomizer *d* as done heretofore, the atomizing of the oil is improved by feeding the air at a more or less steep angle to the outer plain cylindrical 5 side of the conical atomizer *d* through a conical outlet *b*. The conical outlet *b* comprises a conical nozzle of gradually reducing outlet screwed into the outlet *b* of the fan casing *b*.

On the inner wall of the front side of the 10 fan casing *b* are stationary blades *b* which in elevation have portions curved in opposite directions as shown in Figure 2 and direct the air along the outer surface of the conical atomizer *d* through the nozzle *b* and over the edge 15 of the atomizer *d* into the oil atomized by the atomizer *d*. At their outer ends the fixed air directing blades *b* extend around a disc *b* and the rotary blades *b* carried thereon and the disc *b* is fixed to a flange *b* on the sleeve *b* 20 which is held on the oil tube *a* by the cap nut *d*.

The outer portions of the stationary blades *b* in the outer portion of the fan casing *b* are inclined or helical to induce a current to the inner portions of the stationary reversing 25 blades *b* feeding to the atomizing cone, and so overcome the resistance to the air current offered by centrifugal force in the outer portion of the fan casing. The oil tube *a* carrying the sleeve *b*, disk *b* and rotor blades *b* of the fan is 30 driven by any suitable power such as by an electric motor *f*.

The atomizing cone and fan mounting may be constructed as far as possible of one piece to ensure truth and ease of assembly. 35

What I claim and desire to secure by Letters Patent is:—

1. In a rotary liquid fuel burner, a tubular atomizer chamber having its front end open, means for feeding fuel into said atomizer chamber, an annular wall mounted on, and extending outwardly from, the rear end of said atomizer chamber, a second annular wall extending outwardly from the front end of said atomizer chamber with a clearance in between, means for causing a stream of air to flow inwardly between said walls so that it impinges against the outside of said atomizer chamber and passes over the edge at the open end thereof, and fixed vanes extending substantially between said walls and having their inner ends directed so as to cause the air to strike the atomizer chamber in a direction approaching the tangential to the surface of said atomizer chamber. 45

2. In a rotary liquid fuel burner, a rotary tu- 50

- tular atomizer chamber having its front end open, means for feeding fuel into said atomizer chamber, an annular wall mounted on, and extending outwardly from, the rear end of said 5 atomizer chamber, a structure defining a space surrounding said chamber and annular wall, said structure comprising a second annular wall extending outwardly from the front end of the atomizer chamber with a clearance in between, 10 fan blades mounted on the rear side of the first annular wall for causing a stream of air to flow inwardly between said two walls so that it impinges against the outside of said atomizer chamber and passes over the edge of said atomizer 15 chamber at the outer end thereof, and fixed vanes extending substantially between said two walls and, at their outer ends, extending over the edge of the first wall to a position immediately outside the fan blades.
- 20 3. In a rotary liquid fuel burner, a rotary tubular atomizer chamber having its front end open, means for feeding fuel into said atomizer chamber, an annular wall mounted on, and ex-

tending outwardly from, the rear end of said atomizer chamber, a structure defining a space surrounding said chamber and annular wall, said structure comprising a second annular wall extending outwardly from the front end of the 5 atomizer chamber with a clearance in between, fan blades mounted on the rear side of the first annular wall for causing a stream of air to flow inwardly between said two walls so that it impinges against the outside of said atomizer chamber and passes over the edge of said atomizer chamber at the outer end thereof, and fixed vanes extending substantially between said two walls and, at their outer ends, extending over the edge of the first wall to a position immediately 10 outside the fan blades, said vanes being of S formation, having their inner ends directed to cause air to strike the atomizer chamber in a direction approaching the tangential to the surface thereof, and the outer ends directed oppositely to their inner ends 15 20
